(57) CLAIM

I claim the ornamental design for a set top box, as shown and described.

DESCRIPTION

FIG. 1 is a front perspective view of a set top box;

FIG. 2 is a top view of the set top box of FIG. 1;

FIG. 3 is a front view of the set top box of FIG. 1;

FIG. 4 is a side view of the set top box of FIG. 1;

FIG. 5 is another side view of the set top box of FIG. 1;

FIG. 6 is a bottom view of the set top box of FIG. 1; and,

FIG. 7 is a back view of the set top box of FIG. 1.

The portions drawn in broken lines are shown for illustrative purposes only and do not form part of the claimed invention.
